UNITED STATES PATENT OFFICE.

OREN OLMSTEAD, OF SUTTON, CANADA.

CAR-COUPING.

SPECIFICATION forming part of Letters Patent No. 527,392, dated October 9, 1894.

Application filed October 24, 1893. Serial No. 489,066. (No model.)

To all whom it may concern:

Be it known that I, OREN OLMSTEAD, mechanic, a citizen of Canada, of the Township of Sutton, county of Brome, district of Bedford and Province of Quebec, Canada, have 5 invented a new and useful Automatic Car-Coupler, of which the following is a specification.

My invention relates to improvements in 10 coupling and uncoupling cars, and the objects are the following: First, to provide a way by which railroad cars can be uncoupled and coupled without injury to human life or limb; second, to provide an easy and quick 15 way for coupling and uncoupling cars; third, to couple without the assistance of any person; and, fourth, to do it instantaneously. I attain these objects by mechanism as illustrated in the accompanying drawings, in 20 which—

Figure 1 is a view of the entire machine. Fig. 2 is a front end view. Fig. 3 is a side view. Figs. 4 and 4^a represent a coupling rod. Fig. 5 is a section coupling lever, showing the 25 rounded slot end.

The letters on the drawings show the different parts of the coupler, and the same letters refer to the same parts throughout the several figures.

30 A, A, is a coupling rod, which projects through the mouth of the draw bar, a sufficient distance to move spring B at rear end of box, when shoved back. Coupling rod A, A, is about two feet eight inches long, and is made of 35 five-eighths inch round iron, with a turned end about four inches long, with square shoulder to admit spring B, and coiled spring, C.

Fig. 4^a, is crooked coupling rod I have substituted for Fig. 4, as shown in Fig. 1, A, A. 40 The coupling rod can be crooked sufficiently to pass the ends of timbers that hold the draw bars in position.

B, is steel spring some eight inches long made of the best spring steel about one and 45 one-half inches wide with a three-eighths inch hole in the inside box to let coupling rod A, A, pass through. It has a half square shoulder about one and one-half inches long whose coupling rod passes through. It is made convex shape inside from square shoulder to 50 about one and one-fourth inches from the opposite end which end is fastened to the back

end of the box with a small bolt. The back side of spring B is beveled where the bolt passes through, so as to throw the opposite 55 end from the box as shown in the diagram and model.

C, is coiled spring made of one-eighth inch spring wire, and on turned end of coupling rod, A, A, to hold it in position and is placed 60 between spring, B, and end of box.

D, represents the draw bar. The draw bars now in use can be used with my coupler, which will be a great saving in expense.

F, is mouth of draw bar. 65

G, G, is coupling pin twenty inches long which passes through the mouth of draw bar in a horizontal position. The coupling pin is made of the best one and one-half inch round iron or steel, six inches on end to be 70 full size of iron where it holds the link, with tapered end. Commencing about six inches from the tapered end the pin must be turned down to about three-fourths of an inch in size for six inches, then left full size for two inches, 75 with turned groove in the center three-fourths of an inch turned down with square shoulders to three-fourths of an inch in size to hold coupling lever, N, N., then commencing one-half of an inch from groove turned with square shoulder, and leave the balance of the pin three-fourths of an inch in size to hold coil spring g. 80

H, is crossbars and cap that holds coupling lever, N, N in place. The lower bar is a straight piece of wrought iron eight inches 85 long, one and one-half inches wide and three-eighths of an inch thick. The end of the bar rests on slot bearings, attached or cast to the side of the box. It has a pin hole near the center for pivot on coupling lever, N, N. The upper bar is same length and size made with half elliptic circle to allow the action of coupling rod A, A over the inside end. The cap has a hole near the center to correspond with hole in lower bar and for pivot in coupling 90 lever N, N. One end of the cap is placed in slot attachment to inside of the box, while the outer end rests in a groove cast in the outside of the box and is held in place by the lid of the box.

I, I, is pivoted uncoupling lever twenty-two inches long made of one-half inch thick by one and one-eighth inches wide made of wrought iron or steel slightly tapered and

convexed. It has a three-eighths of an inch hole in the center for pivot or bolt and is fastened to the bottom of box by said bolt or pivot. It also has a crank pin Z in rear end. 5 Crank pin Z in lever I, I, is made of one-half of an inch round iron or steel three inches long, and is used to move coupling lever N N in position for uncoupling.

J J, are one-fourth inch rods of iron attached to the opposite ends of uncoupling lever, I, I, for uncoupling cars. There is a rod and handle attachment to the rods, J, J, on the bottom of freight cars which comes to the outside of the cars so that cars can be uncoupled from either side, without going or reaching between them. There is also a chain and lever attachment to ring on end of J, left side of cars projecting one foot or more above the top of box cars for uncoupling 15 freight cars from the top; also a lever attachment for uncoupling from platform of passenger cars, neither of which is shown in the drawings. The lever attachment for the end of freight cars is made of one inch wrought iron one-half inch thick, extending one foot or more above the top of the car with a bolt one-third the distance of car from the lower end of lever. Where it is attached to the end of car the lever should be one and one-half inches wide at the bolt hole, and slightly tapered and convexed toward each end with a staple at the lower end to attach to ring on end of J. The lever for platform of passenger cars is the same only shorter.

35 N, N, is pivoted coupling lever which is held in position by steel spring B for instantaneous coupling of cars. Coupling lever N N is two feet long and made from steel or wrought iron. The center should be one inch wide and five-eighths of an inch thick for pivot and slightly tapered toward the back end, and is made with inside rounded so as to let the lever come into position on steel spring B. The front end of coupling lever, N, N, is made two inches wide 40 sides slightly beveled having a slot in the center rounded to fit the groove on the coupling pin to move coupling pin, G, G.

45 g is coil spring on coupling pin, G, G. This coil spring shunts back into a nozzle on the left side made for said spring to shut into when it is uncoupled.

K K, are lids that cover the box.

50 L is crooked link with a quarter turn to connect with other pin coupling cars. While the process of change is going on with my couplers, I use the straight link.

55 M, is flat spring in the mouth of the draw bar to hold the link from dropping too low to enter the mouth of the next car. This spring should be made of the best spring steel one-fourth of an inch thick and three inches wide and should be slightly thinned where it turns over into the mouth of the draw bar, and is fastened to the under side of draw bar by two 60 screw bolts, also the inner end is slightly flanged where the link rests on it, and is

slightly concaved to carry the link in the center of the spring.

O, is catch that holds button, P. The catch is cast with the side of the box.

P, is iron button that covers the hole in the box opposite the nozzle for inserting or changing the pin when necessary.

V V, are hooks and staples that hold lids K K on the box. The other letters in Figs. 2 75 and 3, correspond to the same letters in Fig. 1.

S, S, are bars of iron on which my coupler is built three feet long and three inches wide and five-eighths of an inch thick. The box is built on these bars of iron, and fastened to 80 the under side of the draw bars by bolts thus giving it the same sliding motion that the draw bars have.

In Fig. 1, E, E, are sides and ends of my double coupling box and are independent of 85 timbers and draw bars to which it is attached.

The left side of box is to contain my automatic arrangement for coupling cars. The right side is used to protect the coupling pin and uncoupling rods. This side may also be 90 used as a box for small tools. The sides, ends and bottoms of the boxes are alike, and made of cast iron some three-eighths of an inch thick in one piece each. The length of the box outside measurement is two feet four inches long.

95 The width of main part is nine inches wide inside, and four inches deep front side while the back side next to the timbers is five inches deep. This is for the outside. The front ends for five inches are to be made with a 100

square angle seven inches in order to pass the ends of the timbers and connect it with the draw bar. The lids are cast iron in two parts and fastened to the box by flanges and hooks.

105 They are cast in two pieces to admit of getting at the coupling pin. The front end lids are five inches wide and fastened to the longer part of lids by hinges. The front lids are cast on an obtuse angle sixteen by five

110 inches, nine inches of lid on an angle and the remaining seven inches will be parallel with the bottom of the box. The nozzle on left side of the box is cast hollow three inches long to hold coil spring g, on coupling pin when uncoupled.

115 The nozzle can be cast with the box or separate and attached with flanges and bolts.

Figs. 4 and 4^a represent a crooked coupling rod which I have substituted for Fig. 4. This is the coupling rod in Fig. 1.

120 Having thus explained my invention, what I claim is—

1. In a car-coupling of the link and pin type, a vertically chambered draw head, a horizontal spring actuated coupling-pin, a spring 125 actuated uncoupling bar, which normally protrudes through said draw head for contact with the draw head of an adjacent car, a spring actuated latch pivotally attached to the opposite end of said uncoupling bar, and 130 a rocker lever engaging at one end with said latch and at the other with said coupling-pin,

whereby the latter is made to automatically engage with a link when two draw heads come together.

2. In a car coupler, a spring pushed coupling pin projecting horizontally across the link opening of the draw-bar in combination with a lever for retracting said pin a catch for locking said lever when the pin is retracted and mechanism for automatically releasing said catch when the draw bar of the two cars contact.

3. In a car coupler; a spring-pushed sliding bar having its free end projecting longitudinally in front of the drawbar head, a spring pushed pin projecting transversely across the link opening of said head; a lever pivotally supported on the draw-bar for retracting said pin; a catch for locking said lever adapted to be released by the inward movement of said sliding bar all being combined and arranged to operate substantially as set forth.

4. In a car coupler; the chambered draw-bar head in combination with the spring M, projecting from the bottom wall thereof substantially as described.

5. A car coupling having a vertically chambered throat or link opening, a spring actuated coupling - pin operating horizontally through the draw head and across said link opening, a lever for retracting said pin, and means substantially as described for operating said retracting lever from either side of a car, and for automatically releasing said coupling-pin at the moment a draw head shall come in contact with that of an adjacent car.

6. In a car coupler; a spring pushed pin projecting into the link opening of the draw-bar, a lever pivotally supported on said draw-bar for retracting said pin, a lever operated from the outer side of the car, for moving said retracting lever a spring catch for locking said retracting lever a spring pushed sliding bar normally holding said spring catch and fitted to release the same when struck by the draw-bar of a companion car all being combined and arranged to operate substantially as described.

7. In a car coupler; the draw-bar in combination with the spring pushed bar, A, the catch, B, operated thereby; the spring pushed coupling pin sliding transversely into said draw-bar the lever, N, for retracting said pin and adapted to be locked by said catch and mechanism for operating said lever.

8. In a car coupler; the chambered draw-bar a box supported thereon a spring pushed coupling pin projecting across the link opening of said bar; a lever for retracting said pin; a spring catch for locking said lever; the spring pushed-bar, A, sliding longitudinally through the head of said draw-bar and operating said catch; the lever, I, for actuating the retracting lever and a connection between said lever, I, and the top or side of the car for actuating the same all being combined and arranged to operate substantially as specified.

OREN OLMSTEAD.
